UNITED STATES PATENT OFFICE

ANDREW T. DUDLEY, OF PORT ARTHUR, TEXAS, ASSIGNOR TO THE TEXAS COMPANY, OF NEW YORK, N. Y., A CORPORATION OF DELAWARE

PUMP

Application filed December 9, 1927. Serial No. 238,749.

The invention relates to improvements in pumps, and more particularly to hot oil pumps of the steam reciprocating type.

One object of my invention is to provide a hot oil pump of the steam reciprocating type wherein auxiliary pumping means which are actuated by the main pump are provided for circulating a cooling medium around the piston rod to keep the piston rod packing cool and consequently in operating condition.

A further object is to provide auxiliary pumping means which are integral with the hot oil pump itself for maintaining a continuous circulation of a cooling medium around at least a portion of the piston rod of rods.

In the drawing, I have shown a hot oil pump of well known construction comprising in general a steam cylinder 10, a valve 20 of liquid chamber 12, having a hot oil inlet 14, and a discharge line 16. The valve chamber 12 is provided with the usual inlet valves 18 and discharge valves 20. A piston rod 22 connects the steam cylinder and the valve or liquid chamber and its operation is regulated by valve controlling mechanism indicated generally at 24.

An auxiliary cylinder 26 is attached to the liquid or valve chamber 12 and is so arranged as to enclose a portion of the piston rod 22. The outer end of the cylinder 26 is formed with a stuffing box 28 in which suitable packing is disposed, being kept in position by a gland 29 so as to prevent leakage around the piston rod. An auxiliary piston 30 is attached to the piston rod 22 and is adapted to form a working fit and to operate within the cylinder 26.

Connected at each end into the lower and upper sides of the auxiliary cylinder 26 are pipes 32, 34, 36, and 38, each of which is provided with a check valve 40. Pipes 32 and 34 are suction lines and pipes 36 and 38 are discharge lines.

A drum or container 42 which is capable of withstanding the full working pressure of the pump is provided and is filled with whatever kind of liquid the pump may be handling. A spiral coil 44, through which cold water or other suitable liquid may be cir-

culated, is arranged on the inside of the drum for the purpose of cooling the liquid contents of the drum.

The suction lines 32 and 34 are connected into the lower end of the drum, while discharge lines 36 and 38 connect with the upper end of the drum. Through the action of the piston 22, together with the check valves 40, the cold liquid contained in the drum is drawn into the auxiliary cylinder 26 where it circulates for a sufficient time to cool the cylinder and the piston rod before it is expelled and forced back again into the drum on the reverse stroke of the piston. It is obvious that on one stroke of piston rod 22, fluid is drawn into the auxiliary cylinder through pipe 34 and simultaneously fluid is expelled from the cylinder through pipe 38. On the return stroke of the piston, fluid is drawn from the drum into the auxiliary cylinder through pipe 32 and expelled from the cylinder through pipe 36.

The hole in the end of the valve chamber through which the piston rod 22 extends is made so as to provide only a good working fit with the piston rod and a small quantity of liquid will necessarily leak through from the chamber 12 into the auxiliary cylinder 26 when the piston of the pump on its discharge stroke moves towards the steam cylinder 10, but simultaneously liquid will be driven from the outer end of the auxiliary cylinder 26 and into the drum. Inasmuch as the drum is entirely filled, a corresponding volume of cooled liquid will be forced out of the drum and into the inner end of the auxiliary cylinder and the pressure in the adjacent ends of the pump and auxiliary cylinder will thus be equalized. On the return stroke of the pump to the right the same process occurs again and the liquid displaced by the piston in the auxiliary cylinder will be forced through pipe 38 into the drum and a corresponding volume of cooled liquid will be drawn out of the drum and into the outer end of the auxiliary cylinder through pipe 34.

Because of the circulation of the cool liquid from the drum through the auxiliary cylinder, that part of the piston rod 22 which moves back and forth through the packing

gland 29 will be kept cool, so that no injury will be done to the packing, and consequently a tight joint is easily maintained.

Under some conditions a small quantity of gas may be liberated by the oil in circulation, and in order to insure that the circulating system may not become gas-bound and consequently have an insufficient quantity of liquid to circulate, a small pipe 46 is provided and extends from the top of the drum 42 to the discharge line 16 from the pump. A valve 48 is provided to control the flow of gas through the line 46 and ordinarily is cracked only enough to permit the small amount of gas which may accumulate in the top of the drum to pass through. The provision of this line also insures that the drum will always be entirely filled with liquid.

In the drawing a single cylinder pump only has been shown, but it is obvious that the same arrangement may be used for a duplex pump and one drum would serve both cylinders.

Apparatus of preferred form and construction has been illustrated and described for the purpose of showing a way in which this invention may be used, but the inventive thought upon which the application is based, is broader than this illustrative embodiment thereof, and I therefore intend no limitations other than those imposed by the appended claims.

I claim:

1. The combination with a hot oil pump having an auxiliary cylinder adjacent the fluid end of the pump and through which the reciprocating piston rod of the pump extends, of a container for a fluid cooling medium, a plurality of pipes connecting the upper and lower portions of the container with the auxiliary cylinder, and means for circulating the cooling medium from the lower portion of the container through the auxiliary cylinder to cool the piston rod and then returning said cooling medium directly to the upper portion of said container.

2. The combination with a hot oil pump having an auxiliary cylinder adjacent the fluid end of the pump and through which the reciprocating piston rod of the pump extends, of a container for a fluid cooling medium, a plurality of pipes connecting the upper and lower portions of the container with the auxiliary cylinder and means actuated by the piston rod for circulating the cooling medium from the lower portion of the container through the auxiliary cylinder to cool the piston rod and then returning said cooling medium directly to the upper portion of said container.

3. The combination with a hot oil pump having an auxiliary cylinder adjacent the fluid end of the pump and through which the reciprocating piston rod of the pump extends, of a container for a fluid cooling medium, a

plurality of pipes connecting the upper and lower portions of the container with the auxiliary cylinder and an auxiliary piston on the piston rod within the auxiliary cylinder for circulating the cooling medium from the lower portion of the container through the auxiliary cylinder to cool the piston rod and then returning said cooling medium directly to the upper portion of said container.

4. The combination with a hot oil pump having an auxiliary cylinder adjacent the fluid end of the pump and through which the reciprocating piston rod extends, of a container for a fluid cooling medium, pipes connecting the opposite ends of the auxiliary cylinder with the upper portion of the fluid container, separate pipes connecting the opposite ends of the auxiliary cylinder with the lower portion of the fluid container, check valves in each of said pipes for controlling the direction of flow of fluid therethrough, and an auxiliary piston on said piston rod within the auxiliary cylinder for maintaining a continuous circulation of the cooling medium from the lower portion of the fluid container through the auxiliary cylinder and to the upper portion of the container.

5. The combination with a hot oil pump having an auxiliary cylinder adjacent the fluid end of the pump and through which the reciprocating piston rod extends, of a container for a fluid cooling medium, means within said container for cooling the cooling medium, a plurality of pipes severally connecting the container with the auxiliary cylinder, and means for circulating the cooling medium from the lower portion of the container through the auxiliary cylinder and back to the upper portion of the container.

6. The combination with a hot oil pump having an auxiliary cylinder adjacent the fluid end of the pump and through which the reciprocating piston rod extends, of a container for a fluid cooling medium, a plurality of pipes severally connecting the container with the auxiliary cylinder, means for circulating the cooling medium from the lower portion of the container through the auxiliary cylinder and back to the upper portion of the container, and a valved outlet in the upper end of the container for the release of any gases which may accumulate during the circulation of the cooling medium.

In witness whereof I have hereunto set my hand this 30th day of November, 1927.

ANDREW T. DUDLEY.
